UNITED STATES PATENT OFFICE.

JOSEPH GRASSER, OF NETSTAL, SWITZERLAND.

APPARATUS FOR THE STEAMING OF FABRICS.

1,340,482.

Specification of Letters Patent. Patented May 18, 1920.

Application filed January 30, 1920. Serial No. 355,114.

To all whom it may concern:

Be it known that I, JOSEPH GRASSER, a citizen of the French Republic, and resident of Netstal, Canton of Glaris, Switzerland, 5 have invented a new and useful Apparatus for the Steaming of Fabrics, of which the following is a full, clear, and exact specification.

The steaming of fabrics is usually effected 10 by causing them to pass through a box supplied with steam, which has the drawback that, for a short steaming, the tissue must receive a very great speed and that for goods, which as for instance goods with dis- 15 charging effects produced by hydrosulfite must be steamed with exclusion of air, a long time. For instance, $1\frac{1}{2}$ hours are necessary for producing in the steaming box a steam atmosphere free of air. These draw- 20 backs are avoided by the apparatus for the steaming of textile fabrics which forms the object of the present invention, hereby that the fabric remains stationary in the steaming box during the steaming process and 25 that the air is expelled completely from the steaming box in a very short time, for instance within 5 minutes to $\frac{1}{4}$ of an hour.

In this apparatus, the steaming box, 30 which is open underneath and has well insulated walls, is placed above the chamber for the introduction of the goods which is provided in its lower part with air and steam outlet, so that the steam, which passes into the steaming box from above and is 35 regularly distributed over the entire ground surface of the steaming box, can expel the air in a short time out of the steaming box downward through the said introduction chamber to the outside, and there is provided 40 a lifting device for a star shaped fabric holder for the spiral suspension of the fabric to be steamed, by means of which the fabric holder, on which the fabric is suspended and which is introduced into the introduction 45 chamber only after all the air has been ex- 90 pelled from the steaming box, can be drawn up slowly out of the specified introduction chamber into the box previously filled ex- 50clusively with steam, in order that it may 95 remain quietly in it during the steaming process, and be again let slowly down into the introduction chamber after the comple- 100tion of the steaming.

In order to attain the uniform expulsion 55 of the air, by means of the steam throughout the entire ground surface of the steam- 110

ing box, this latter is preferably provided at the top with a steam distributing device. This steam distributing device may, for instance, consist of a distributing cone, placed 60 vertically within a trough in the form of a truncated cone, against which the steam jet introduced in the upper part of the steam box impinges, so that the steam, after suc- 65cessive deflections on the distributing cone, 70 the trough and the ceiling of the steaming box is distributed over a horizontal grating under which is arranged a hollow protecting cone, the lower end of which does not quite reach to the lateral wall of the steam- 75ing box and conducts the water of condensa- 80tion, which is formed, into a collecting channel.

At the inner periphery of the steaming box, there may be placed a steam heating 75 coil, and the introduction chamber is pro- 90vided with a door, after the opening of which it becomes possible to move the star supporting the fabric resting upon the three vertical rods of a carriage, into and out of 95 the introduction chamber.

In the accompanying drawing a constructional example of the new apparatus is illus- 100trated as follows:

Figure 1 shows partially a side elevation 85 and partially a vertical section;

Fig. 2 shows a vertical section taken at right angles to Fig. 1;

Fig. 3 shows a horizontal section approxi- 90mately on the line 1-1 of Fig. 1. 95

The steaming box A, which is open underneath and has its walls well insulated, rests upon the base structure B of masonry which represents the chamber for the introduction of the goods, is of horseshoe horizontal sec- 95 tion, and is provided above with a strong cover plate a showing the vertical reinforce- 100ment a¹ in front,—and upon which the front part of the steaming box is supported. The front side of the base structure B can be 105 closed by means of a sliding door C of wood, which is counter-balanced by two weights z suspended over firmly supported revolute rollers d by means of the wire ropes e in order to render possible the easy opening 110 of the door C. The two front walls i of the structure are protected with angle irons e against which the door can be pressed by means of the bolting devices f. The upper edge of the door is pressed by means of U-shaped clamps j and wing screws k against the reinforcement a¹.

Beneath the free opening *s* of the pipe *l* which is devised to serve for the supply of steam to the upper part of the steaming box, there is arranged a distributing cone *m*, upon which the steam jet rushing out of *s* strikes. The steam rebounding from *m* is caught up by the trough *n* arranged around *m* and thereby directed against the top or ceiling of the steaming box, so that, owing 10 to this repeated rebounding, the inflowing steam has its original momentum reduced.

At a distance, preferably about 25 cm. from the top or ceiling of the steaming box, there is arranged beneath the trough *n* a metal grating *o*, which enables the steam to penetrate downward, distributed throughout the entire ground surface of the steaming box. Underneath the metal grating *o* is placed a hollow protecting cone *p*, the lower end of which is carried to a short distance away (say about 5 cm.) toward the lateral wall of the steaming box, and has for its purpose to draw off the water, produced by the condensation, into a collecting channel *t* formed of a sloping metal strip. In consequence of its inclined position, this channel *t* directs the steam passing between the protecting cone *p* and the side wall of the box downward against the middle of 30 the steaming box. In this manner a regular expulsion of the air by the steaming out of the box *A* is obtained from above downward when steam is passed through the pipe *l* into the box originally filled with air.

35 At the inner periphery of the box *A* is placed a steam coil *D* which enables the box to be warmed previously to some extent, that is to say to steam at higher temperatures. At the half height the side wall of the steaming box is provided with a recess (not shown in the drawing) which is intended for the holding of a bent thermometer.

e indicates a pipe connected underneath to the structure *B*, through which pipe there 45 can flow away to the outside, as well the air expelled from *A* through *B*, as also, during the steaming, the steam in excess.

For the introduction of the fabric to be steamed into the apparatus, there is provided a six-armed star *F*, the arms of which are provided with brass hooks on which the fabric to be steamed is suspended spirally outside the apparatus, and three arms of the aforesaid star rest upon three vertical 55 rods *v* of a movable carriage *G*.

When, by the inrush of steam through the pipe *l*, the air has been driven out of the box *A*, the carriage *G*, together with the star *F* having the fabric to be steamed suspended 60 upon it, is passed into the structure *B*, after opening the door *C*, and the star *F* is then suspended, by means of a hook provided thereon, to a chain *H* passing over the roller *x*, *y*, and by winding up this chain upon a 65 small iron hasp *I*, lodged in the masonry

structure *B*, the star is slowly drawn up, so that it is lifted off from the rods *v* of the carriage *G* and drawn into the steaming box *A*. After the removal of the carriage out of the masonry structure *B* and the closure of the door *C*, the steam is further allowed to pass through *l* into the apparatus. As soon as the requisite steaming has been effected, the supply of steam is shut off at *l*, and the door *C* is again opened so that the steam 70 collected in the lower structure can escape, the carriage *G* is again pushed into the lower structure *B* and, by means of the hasp *I*, the star *F* is slowly lowered, so that three of its arms can be taken up by the rods *v* of the carriage, whereupon the carriage *G*, laden with the steamed fabric can be again removed, out of the under structure, and another carriage bearing a star provided with another fabric to be steamed can be 75 introduced into the lower structure.

Instead of being formed by a lower structure of masonry, the chamber for the reception of the goods may be made of metal, and the construction both of the steaming 80 box and of the introduction chamber may be made of the same metal sheets.

What I claim is:

1. An apparatus for the steaming of fabrics, comprising a steam box, open underneath, having well insulated walls and provided with an upper steam inlet and an upper device distributing the steam uniformly over the entire ground surface of the steam box, a goods introduction chamber placed 95 below the said steaming box and having, at its lower part, an outlet for air and steam, so that the steam passing from above into the steam box can drive the air out of the steam box downward through the goods introduction chamber to the said outlet; a star shaped fabric holder for the spiral suspension of the fabric to be steamed, and a lifting device by means of which the said fabric holder bearing the fabric can be drawn up 100 slowly from below out of the goods introduction chamber into the steam box previously filled with steam, can be left stationary during the steaming process, and, after the steaming, be again lowered slowly into 105 the introduction chamber.

2. An apparatus for the steaming of fabrics having a steam distributing device comprising a trough, having the form of a truncated cone, a distributing cone placed upright in the said trough, a horizontal grating below the said trough and a hollow protecting cone placed below the said grating, the lower end of which does not reach to the lateral steaming box wall, and which directs 120 the water of condensation, which forms, into 125 a collecting channel.

3. An apparatus for the steaming of fabrics, comprising a steam box, open underneath, having well insulated walls and pro- 130

- vided with an upper steam inlet and an upper device distributing the steam uniformly over the entire ground surface of the steam box, a goods introduction chamber placed below the said steaming box and having, at its lower part an outlet for air and steam, so that the steam passing from above into the steam box can drive the air out of the steam box downward through the goods introduction chamber to the said outlet, a star shaped fabric holder for the spiral suspension of the fabric to be steamed, and a lifting device by means of which the said fabric holder bearing the fabric can be drawn up slowly from below out of the goods introduction chamber into the steam box previously filled with steam, can be left stationary during the steaming process, and, after the steaming, be again lowered slowly into the introduction chamber, and a steam heating coil provided at the inner periphery of the steam box.
4. An apparatus for the steaming of fabrics, comprising a steam box, open underneath, having well insulated walls and provided with an upper steam inlet and an upper device distributing the steam uniformly over the entire ground surface of the steam box, a goods introduction chamber placed
- below the said steaming box and having, at 30 its lower part, an outlet for air and steam, so that the steam passing from above into the steam box can drive the air out of the steam box downward through the goods introduction chamber to the said outlet, a star 35 shaped fabric holder for the spiral suspension of the fabric to be steamed, and a lifting device by means of which the said fabric holder bearing the fabric can be drawn up slowly from below out of the goods introduction chamber into the steam box previously filled with steam, can be left stationary during the steaming process, and, after the steaming, be again lowered slowly into the introduction chamber, and a transport 40 carriage having several vertical rods for supporting the star shaped fabric holder when it is introduced into the goods introduction chamber and when it is removed from this latter.
- 50

In witness whereof I have hereunto signed my name this 10th day of January, 1920, in the presence of two subscribing witnesses.

JOSEPH GRASSER.
